LOOSE-LEAF STORAGE DEVICE

Leonard D. Kerwin, Detroit, Mich.

Application December 21, 1953, Serial No. 399,200

9 Claims. (Cl. 281—44)

This invention relates to a looseleaf storage device, and more particularly to a sheet storage magazine together with a sheet ejecting device, and a second storage magazine removably positioned over the first storage magazine.

It is the object of the present invention to provide a looseleaf storage device, which can store a series of looseleaf sheets, together with a sheet ejecting mechanism.

It is the further object of the present invention to provide a secondary sheet storage device removably associated with the first sheet storage mechanism.

It is the further object of the present invention to provide a looseleaf sheet storage device, together with a suitable writing platform forming a part thereof.

It is the object of the present invention to provide a novel and simplified sheet storage mechanism, which is simplified in structure and which efficiently carries out the above defined objects.

These and other objects will be seen from the following specification and claims, in conjunction with the appended drawing, in which:

Fig. 1 is a plan view of the present looseleaf sheet storage device.

Fig. 2 is a side elevational view thereof.

Fig. 3 is a section taken on line 3—3 of Fig. 1.

Fig. 4 is an elevational section of the bottom portion of the sheet storage device with a writing platform mounted thereon.

Fig. 5 is a section taken on line 5—5 of Fig. 2; and

Fig. 6 is a fragmentary section taken on line 6—6 of Fig. 5, illustrating the sheet ejecting mechanism on an enlarged scale.

It will be understood that the above drawing illustrates merely a preferred embodiment of the invention, and that other embodiments are contemplated within the scope of the claims hereafter set forth.

Referring to the drawing, the present looseleaf sheet storage device includes a hollow wedge-shaped base 11, which includes the spaced upwardly inclined side walls 12, whose top edges are inclined upwardly at 13, as shown in Fig. 2.

Opposed slots 14 are formed in the top edges of side walls 12, intermediate their ends, and are adapted to cooperatively receive the opposed ears 31 which project laterally from opposite sides of the platform 30, when said platform is positioned upon the base 11, in the manner illustrated in Fig. 4, using the same as a writing desk.

The hollow base 11 includes the bottom wall 15, the upright rear wall 16 and the upright front wall 17, as illustrated in Fig. 3.

A horizontally disposed ledge 18 is secured to front wall 17 and projects inwardly thereof intermediate its top and bottom longitudinal edges, said ledge preferably extending between side walls 12, as illustrated in Fig. 5.

A transverse slot 19 is formed throughout the front wall 17 at its lower end adjacent bottom wall 15, through which the top of a series of sheets of paper 20 resting on base 15 may be ejected, in the manner hereafter described.

As generally indicated at 21 in Fig. 2, there is provided above the hollow base 11, a hollow sheet enclosure which includes the spaced upright side walls 22, whose upper edges are horizontally disposed, but whose lower edges are tapered upwardly and cooperatively register with the upwardly tapering edges 13 of base 11, in the manner illustrated in Fig. 2. Said enclosure also in-

cludes the upwardly inclined bottom 23, the upright front end 25 and the substantially upright rear end 28, which is slightly inclined upwardly as shown in Fig. 3.

As shown in Fig. 3, the upright front and rear ends 24 and 27, respectively, and as illustrated in the drawing the said depending ends 24 and 27 are positionable around and co-extensive with the front and rear end walls 17 and 16, respectively of base 11. Furthermore as shown in Fig. 2, the said front end 24 of the enclosure includes at its opposite sides the upright rearwardly extending portions 24' which engage around the front portions of the side walls 12 of the hollow base 11.

By this construction, the hollow base is snugly interlocked and positioned within and between the portions of the front and rear ends of enclosure 21, which extend below said enclosure bottom 23.

The hollow sheet enclosure 21 is open at its upper end as defined by the top marginal edge 26. The upright sides 22 have opposed notches 32 formed in their upper edges 26 intermediate their ends and are adapted to cooperatively receive the outwardly projecting ears 31

which extend from opposite sides of the horizontally disposed platform 30, which is nested within the upper open end 26 of sheet enclosure 21. Platform 30 at its forward end has a downwardly depending flange 33, which rests upon the bottom 23 of said enclosure, the opposite end of platform 30 supportably resting upon the transverse ledge 29 which projects inwardly from the rear end 28, as shown in Fig. 3, being positioned downwardly of its upper edge. The flange 33 of platform 30 terminates at its opposite ends in the side flanges 34, which depend from opposite sides of platform 30 and snugly and cooperatively engage the inner surfaces of the upright sides 22.

As illustrated in Figs. 2, 5 and 6, there is provided a sheet ejecting mechanism upon the side wall 12 of the hollow base 11. This ejector includes the hollow elongated housing 35, which is oppositely slotted at 36 and contains upon its interior the coiled spring 37. Transversely arranged arm 38 at one end extends through the slots 36 and is positioned at the forward end of housing 35 and operatively retained in such position by coiled spring 37. Handpiece 40 is secured upon the outer end of arm 38 and is adapted to slidably engage the outside surface of housing 35 as arm 38 is manually retracted against said spring.

The sheet engaging foot 41 is pivotally mounted at the reduced inner end 41' of arm 38 and has a sheet engaging element 42 at its lower end adapted to operatively and frictionally engage the top-most of a series of sheets 20, shown in Fig. 3. The sheet engaging element 42 is constructed of a flexible resilient substance, such as sponge rubber or the equivalent, adapted to frictionally engage the top of said sheets 20.

In operation, the ejector arm 38 is withdrawn by the handle 40 with the sheet engaging element 42 moving rearwardly over the top sheet 20 within base 11. Thereafter, the handle 40 is released and automatically returns to the position shown in Fig. 6 under the action of spring 37, with the sheet engaging element 42 frictionally engaging and forwardly projecting the top sheet 20 outwardly of base 11 through the slot 19.

In operation, there is provided the hollow base 11, within which looseleaf sheets may be stored and ejected as desired. There is also provided an interlockingly arranged secondary sheet enclosure 21, which is positioned upon the base 11 with its downwardly depending end portions retainingly engaging the opposite ends of said base to provide a compact portable unit.

Enclosure 21 is also adapted to contain sheets of paper, such as the sheets 20 after they have been used, or for any similar storage purpose.

In operation, with the base 11 resting upon a table or other flat surface, the sheet enclosure 21 may be manually removed and placed to one side. Thereafter, the cover element 30 may be manually removed by grasping the ears 31 and lifting the same, after which said cover 30 may be re-applied to the top surface of base 11 with the same ears 31 cooperatively positioned within the opposed recesses 14 formed in the top edges of side walls 12 of

said base. The depending flange 33 of the cover 30 or platform, supportably bears upon the ledge 18, and the rear edge of said cover rests upon the top edge of the rear wall 16, in the manner shown in Fig. 4. By this construction, there is provided a convenient writing platform.

Having described my invention, reference should now be had to the claims which follow for determining the scope thereof.

I claim:

1. A looseleaf sheet storage device comprising a hollow wedge-shaped base including a bottom wall, upwardly inclined upright side walls, and upright front and rear end walls, a horizontally disposed ledge secured to and projecting inwardly of said front end wall intermediate its top and bottom, an upwardly inclined writing platform positioned within the open top of said base with its forward end resting upon said ledge and its rear end resting upon said rear end wall, there being opposed slots in the top edges of side walls intermediate their ends, and opposed ears projecting laterally from opposite sides of said platform intermediate its ends supportably positioned within said slots.

2. A looseleaf sheet storage device comprising a hollow wedge-shaped base, including a bottom wall, upwardly inclined upright side walls, and upright front and rear end walls, a horizontally disposed ledge secured to and projecting inwardly of said front end wall intermediate its top and bottom, an upwardly inclined writing platform positioned within the open top of said base with its forward end resting upon said ledge and its rear end resting upon said rear end wall, a downwardly depending flange at the front end of said platform resting upon said ledge, and depending flanges at the sides of said platform nested within said side walls.

3. A looseleaf sheet storage device comprising a hollow wedge-shaped base including a bottom wall, upwardly inclined upright side walls, and upright front and rear end walls, a horizontally disposed ledge secured to and projecting inwardly of said front end wall intermediate its top and bottom, an upwardly inclined writing platform positioned within the open top of said base with its forward end resting upon said ledge and its rear end resting upon said rear end wall, the front end wall of said base at its bottom having a transverse slot throughout, said base providing a storage magazine for a stack of loose sheets of paper, and a reciprocal sheet ejector mounted on one side wall projecting above said stack of sheets and operatively engageable with the top sheet for projecting the same through said slot.

4. A looseleaf sheet storage device comprising a hollow wedge-shaped base including a bottom wall, upwardly inclined upright side walls, and upright front and rear end walls, a horizontally disposed ledge secured to and projecting inwardly of said front end wall intermediate its top and bottom, an upwardly inclined writing platform positioned within the open top of said base with its forward end resting upon said ledge and its rear end resting upon said rear end wall, the front end wall of said base at its bottom having a transverse slot throughout, said base providing a storage magazine for a stack of loose sheets of paper, a reciprocal sheet ejector mounted on one side wall projecting above said stack of sheets and operatively engageable with the top sheet for projecting the same through said slot, said ejector including an oppositely slotted elongated housing, an arm extending transversely through the slots of said housing at its forward end, a handle on the outer end of said arm, a sheet engaging foot pivotally mounted upon the inner end of said arm, and a coiled spring in said housing normally maintaining said arm at the forward end of said housing slots, said handle being rearwardly movable against said spring whereby when released it projects forwardly with said foot forwardly displacing a sheet of paper.

5. A looseleaf sheet storage device comprising a hollow wedge-shaped base including a bottom wall, upwardly inclined upright side walls, and upright front and rear walls, and a hollow sheet enclosure mounted upon said base including an upwardly inclined bottom, upright sides, and substantially upright front and rear ends, said front and rear ends extending below said bottom and positionable around and co-extensive with the front and rear end walls of said base, a horizontally disposed platform within the top open end of said enclosure, a flange depending downwardly from the front end of said platform resting upon said bottom, a ledge projecting inwardly of said rear end adjacent its top, the rear end of said platform resting upon said latter ledge.
- 10 15 6. The storage device of claim 5, there being opposed slots in the top edges of said sides intermediate their ends, and opposed ears projecting laterally from opposite sides of said platform intermediate its ends supportably positioned within said slots.
- 20 7. The storage device of claim 5, the front end wall of said base at its bottom having a transverse slot throughout, said base providing a storage magazine for a stack of loose sheets of paper, and a reciprocal sheet ejector mounted on one side wall projecting above said stack of sheets and operatively engageable with the top sheet for projecting the same through said slot.
- 25 8. The storage device of claim 5, the front end wall of said base at its bottom having a transverse slot throughout, said base providing a storage magazine for a stack of loose sheets of paper, a reciprocal sheet ejector mounted on one side wall projecting above said stack of sheets and operatively engageable with the top sheet for projecting the same through said slot, said ejector including an oppositely slotted elongated housing, an arm extending transversely through the slots of said housing at its forward end, a handle on the outer end of said arm, a sheet engaging foot pivotally mounted upon the inner end of said arm, and a coiled spring in said housing normally maintaining said arm at the forward end of said housing slots, said handle being rearwardly movable against said spring whereby when released it projects forwardly with said foot forwardly displacing a sheet of paper.
- 30 35 9. A looseleaf sheet storage device comprising a hollow wedge-shaped base including a bottom wall, upwardly inclined upright side walls, and upright front and rear walls, a hollow sheet enclosure mounted upon said base including an upwardly inclined bottom, upright sides, and substantially upright front and rear ends, said front and rear ends extending below said bottom and positionable around and co-extensive with the front and rear end walls of said base, a horizontally disposed platform within the top open end of said enclosure, a flange depending downwardly from the front end of said platform resting upon said bottom, a ledge projecting inwardly of said rear end adjacent its top, the rear end of said platform resting upon said latter ledge, a horizontally disposed ledge secured to and projecting inwardly of said front end wall intermediate its top and bottom, said sheet enclosure being removable from said base, and said platform being removable from said sheet enclosure and adapted for positioning within the open top of said base, with its forward end resting upon said ledge and with its rear end resting upon said rear end wall.
